WALLPAPER PASTING MACHINE AND
TRIMMER

Charles E. McClure, Hamilton, Ohio

Application October 9, 1946, Serial No. 702,289

2 Claims. (Cl. 91--14)

1

This invention relates to improvements in devices for papering walls, and more particularly to the provision of a portable device by means of which the wall paper can be pasted and cut rapidly and properly.

It is an object of the invention to provide a device which will paste and trim the edges of wall paper at the same time without folding the paper, eliminating the waste of paper, as the entire roll of wall paper can be used in one continuous strip if needed.

A further object is the provision of a device in which both edges of the wall paper are matched for a smooth even job on the wall, with no wrinkles or folding.

A further object is to provide a wall paper trimming device having adjustable knives to accommodate different widths of paper.

An object is the provision of a device for pasting and cutting the edges of wall paper, which device is portable and can be conveniently carried to any part of a room to facilitate the papering of a wall and save considerable time.

These and other objects are attained by the novel construction and arrangement of parts hereinafter described and illustrated by the accompanying drawings, forming a part hereof, and in which:

Fig. 1 is a side view of a device embodying the invention.

Fig. 2 is a plan view of the device.

Fig. 3 is a sectional view taken on the line 3--3 of Fig. 2.

Fig. 4 is a sectional view similar to Fig. 3 except showing a rewinding roller.

Fig. 5 is a view of a rewinding roll used with the device.

Referring to the drawings, in Fig. 1, the device for pasting and cutting wall paper is shown to comprise a frame having end members formed of bars 1, 2, 3 bolted or otherwise secured together, the bar 3 being vertical and the bars 1 and 2 forming a triangular support. A cross bar 4 extends from bar 1 to bar 2 and supports shafts 5 and 6. At one end of the frame a bar 7 spaced from bar 4 further supports shafts 5 and 6. Shaft 5 carries a roll of wall paper and shaft 6 has fixed thereon a brush 8 for pasting the paper.

Each shaft 5 and 6 has squared ends to receive a crank 9 for rotating the shafts, the crank being interchangeable. At the upper end of bars 3 is a rod 10 to which is attached a strap for carrying the device about the shoulders.

Fixed to shaft 6 is a gear 11, in mesh with a gear 12 fixed to a shaft 13 supported by bars 2.

2

The bars 1 support a shaft 14 which carries at each end cutters 15. The peripheral edge of the cutters 15 is arranged in engagement with the outer periphery of a pressure roller 16. The shaft 13 carries the pressure roller 16 which cooperates with the brush 8 to paste the paper, the paste being in a trough 17 below the brush 8, the trough having an upstanding plate extension 18 over which the paper passes and which prevents the paste from splashing. The strap 19 can be conveniently fitted about the shoulders of an operator.

On bars 2 are hooks 20 adapted to support a rewind shaft 21 for rewinding paper from shaft 5.

In operation, the roll of wall paper is placed on the shaft 5 and wound by the crank 9 between the brush 8 and the pressure roll 16 to apply paste to the wall paper. The cutters 15 are positioned adjacent the pressure roll and at the edges of the wall paper, the movement of the paper through the machine rotating the cutters 15 and trimming the edges.

As shown in Fig. 1, the paper passes over the plate 18 to the operator applying the paper to a wall or ceiling. When it is desired to accurately match the designs, the paper is rewound on the shaft 20, which has a squared end to receive the crank 9. (See Fig. 4.)

The operator turns crank 9 to rotate brush 8 to provide fresh paste, the pressure roller 16 insuring proper pasting and the cutters 15 trimming the edges of the paper.

It will be seen that there has been provided a simple and effective device by means of which it is not necessary to fold the wall paper, nor to trim the edges by hand, thus providing accurate operation and greatly lessening the time required to paper a wall. Also, the matching of the designs is facilitated by the rewind shaft 20. This enables the paper to be drawn back a short distance to match the designs without wasting paper.

It will be seen that there has been provided a simple and effective device for pasting wall paper, trimming the edges so that the edges are matched for a smooth even applying of the paper without wrinkles or folding.

The above description is to be considered as illustrative and not limitative of the invention of which modifications can be made without departing from the spirit and scope of the invention as set forth in the appended claims.

The invention having been described, what is claimed is:

1. In a wallpaper pasting and trimming ma-

chine, a frame, a first horizontally-disposed rotatable shaft operatively connected to said frame for the support thereon of a roll of wallpaper, a trough arranged adjacent one side of said frame and dependingly carried by the latter, said trough adapted to contain paste therein, a second horizontally-disposed rotatable shaft spaced from said first shaft and carried by said frame, said second shaft being disposed over said trough, a brush secured to said second shaft and rotatable in said trough, a third rotatable shaft spaced above said brush and carried by said frame, a pressure roller secured to said third shaft and coacting with said brush to receive the wallpaper therebetween, a fourth rotatable shaft spaced from said third shaft and supported on said frame, a pair of spaced, parallel cutters arranged transversely on said fourth shaft and secured to the latter, the peripheral edges of said cutters being arranged in engagement with the outer periphery of said pressure roller, a plate extension projecting upwardly from one side of said trough and secured thereto, the upper end of said plate extension being arranged above the uppermost of said shafts, said wallpaper being trained between said third shaft and brush and over said cutters and plate extension, gear means operatively connecting said second, third and fourth shafts together, and manually-operable means connected to one end of said third shaft for rotating said shafts to thereby successively cause said brush to apply paste to a surface of the wallpaper and trim said paper to a predetermined size.

2. In a wallpaper pasting and trimming machine, a frame, a first horizontally-disposed rotatable shaft operatively connected to said frame for the support thereon of a roll of wallpaper, a trough arranged adjacent one side of said frame and dependingly carried by the latter, said trough adapted to contain paste therein, a second horizontally-disposed rotatable shaft spaced from said first shaft and carried by said frame, said

second shaft being disposed over said trough, a brush secured to said second shaft and rotatable in said trough, a third rotatable shaft spaced above said brush and carried by said frame, a pressure roller secured to said third shaft and coacting with said brush to receive the wallpaper therebetween, a fourth rotatable shaft spaced from said third shaft and supported on said frame, a pair of spaced, parallel cutters arranged transversely on said fourth shaft and secured to the latter, the peripheral edges of said cutters being arranged in engagement with the outer periphery of said pressure roller, a plate extension projecting upwardly from one side of said trough and secured thereto, the upper end of said plate extension being arranged above the uppermost of said shafts, said wallpaper being trained between said third shaft and brush and over said cutters and plate extension, gear means operatively connecting said second, third and fourth shafts together, manually-operable means embodying a crank connected to one end of said third shaft for rotating said shaft to thereby successively cause said brush to apply paste to a surface of the wallpaper and trim said paper to a predetermined size, and strap means connected to said frame for carrying said machine.
